[57] CLAIM

The ornamental design for a truck trailer body, as shown and described.

DESCRIPTION

FIG. 1 is a left front perspective view of a truck trailer body, showing my new design;

FIG. 2 is a front elevational view, thereof;

FIG. 3 is a rear elevational view, thereof;

FIG. 4 is an elevational view of one side, thereof;

FIG. 5 is an elevational view of the other side, thereof;

FIG. 6 is a top plan view thereof; and,

FIG. 7 is a bottom plan view, thereof.

The representations of front support jack and rear wheel assemblies, shown in broken lines in FIGS. 1 and 4, are included solely for illustrative purposes, and form no part of the claimed design.

FIG. 1.

FIG. 2.

FIG. 3.

FIG. 6.

FIG. 7.
